UNITED STATES PATENT OFFICE.

BENJAMIN SCHWARTZMAN, OF NEW YORK, N. Y., ASSIGNOR TO SAMUEL SHAPIRO, JOSEPH SHAPIRO, SOLOMON SHAPIRO, DAVE SHAPIRO, AND MORRIS BERMAN, ALL OF NEW YORK, N. Y., COPARTNERS DOING BUSINESS UNDER THE NAME OF RELIANCE METAL SPINNING COMPANY, OF NEW YORK, N. Y.

DESIGN FOR A SOCKET-COVER FOR GAS AND ELECTRIC FIXTURES.

49,041.

Specification for Design.

Patented May 9, 1916.

Application filed January 12, 1916. Serial No. 71,792. Term of patent 7 years.

To all whom it may concern:

Be it known that I, BENJAMIN SCHWARTZMAN, a citizen of the United States, residing at the city of New York borough of Brooklyn, in the county of Kings and State of New York, have invented a new, original, and ornamental Design for a Socket-Cover for Gas and Electric Fixtures, of which the following is a specification, reference being had to the accompanying drawing, forming part thereof.

Figure 1 is a plan view of a socket cover for gas and electric fixtures, as shown. new design. Fig. 2 is a side elevation of the design shown in Fig. 1.

I claim:

The ornamental design for a socket cover for gas and electric fixtures, as shown.

BENJAMIN SCHWARTZMAN.
